UNITED STATES PATENT OFFICE.

CONYERS BUTTON, OF PHILADELPHIA, PENNSYLVANIA.

DESIGN FOR STOCKING FABRIC.

Specification forming part of Design No. 6,671, dated May 27, 1873; application filed May 13, 1873.

To all whom it may concern:

Be it known that I, CONYERS BUTTON, of the city and county of Philadelphia, State of Pennsylvania, have invented a Design for a Stocking Fabric, of which the following is a specification:

The figure in the accompanying drawing represents sufficient of a stocking fabric to illustrate the design, the remainder being merely a repetition of that which appears.

The design consists of a series of parallel stripes, *a*, *b*, and *c*, and of two narrower stripes, *d* and *e*, of different shades or colors at either side of the same, the whole being arranged

upon a plain ground, preferably of a lighter shade or color than that of the stripes.

Irrespective of the colors employed, I claim—

The design for a stocking fabric, substantially as described, and as represented in and by the accompanying drawing.

In testimony whereof I have signed my name to this specification in the presence of two subscribing witnesses.

CONYERS BUTTON.

Witnesses:
